ELECTRIC-LAMP SOCKET.

1,177,319.

Specification of Letters Patent. Patented Mar. 28, 1916.

Application filed January 26, 1915. Serial No. 4,457.

To all whom it may concern:

Be it known that we, GILBERT W. GOODRIDGE and GEORGE B. THOMAS, both citizens of the United States of America, and both residing at Bridgeport, in the county of Fairfield and State of Connecticut, have invented a certain new and useful Improvement in Electric-Lamp Sockets, of which the following is a specification.

Our invention relates to electric lamp sockets and particularly to combined sockets and shade holders, the object of our invention being to provide an improved device of this character having the features of novelty hereinafter pointed out and shown in the accompanying drawings in which—

Figure 1 is a broken sectional elevation of a key socket in which our invention is illustratively embodied; Fig. 2 is a plan of the lamp-receiving end thereof; Fig. 3 is a partial elevation of the porcelain body of the socket; Fig. 4 is a section therethrough on the line 4—4, Fig. 2, to show the switch spindle and key, the thumb piece being shown detached; Fig. 5 is a section on the line 5—5, Fig. 2, to show the wire passages to the front of the socket; Figs. 6 and 7 are perspective views of the electrical connections to the switch terminal and screw shell terminal respectively; Fig. 8 is a plan of the inner end of the insulating body of the socket; Fig. 9 is an interior plan of the inner button of the socket body; and Fig. 10 is an interior plan of the outer button of the socket body.

In the construction here shown the present socket comprises a one-piece metallic casing 10 closed at one end except for the nipple 11 through which the wires 12 and 13 are led to the interior and by which the fitting may be mounted on any suitable support such as a wire conduit, fixture pipe or the like in well understood fashion. The opposite end of the casing is outwardly flared at 14 to afford a rounded shoulder against which a correspondingly shaped flare 15 of the insulating body 16 of the receptacle fits. This end of the casing is further extended beyond the end of the body 16 as a ring 17 adapted to receive the usual bead of a shade holder which is engaged and held by any suitable means, such as the set screws 18, carried by the ring 17. A bridge-like bracket 19 secured with the casing 10, against the exterior shoulder 20 of the nipple 11 by the

outwardly spread inner end 21 of the latter, is provided with feet 22 resting in seats 23 in the insulating body 16 and tapped to receive the securing screws 24 by which the body is held within the casing. In switched sockets, such as here shown, the socket body comprises a pair of insulating buttons *a* and *b* perforated in register to permit the passage of the securing screws 24 therethrough. The well 25 in the outer face of button *b* is of greater diameter than the screw hole to afford a shoulder for the screw head, while the inner end of the hole through this button *b* is also enlarged to afford a well 26 for the reception of a split washer 27 on the screw 24 by which the latter is restrained from dropping out when it is unscrewed from the bracket 19. Obviously the socket body is secured within or detached from the casing 10 by the manipulation of the screws 24 from the open lamp-receiving end of the socket. The buttons *a* and *b* are also perforated to afford continuous passages 28 and 29 through which the wires 12 and 13 may be led to wells 30 and 31 in the front or lamp-receiving end of the socket body. The well 30 forms merely a bay opening from the main well 32 in which the screw shell terminal 33 is seated and secured by the two screws 34. The heads of the latter rest in recesses 36, 37 (Fig. 10) on the inner face of the button *b* and passing through the button and the base flanges 38 of the screw shell take into tapped holes in the usual reinforcing yoke 39 (Fig. 2). Seated in the bay 30 to one side of the wire passage 28 is the angled end 40 of a strap 41, carrying the binding screw 42 beneath the head of which the bared end of the wire 13 is secured. The strap passes down in the well 32 outside the screw shell 33 and its inner end 43 is angled into a seat beneath the screw shell terminal 33 and perforated to permit the passage of the screw 34 therethrough. The screw shell is thus constantly in electrical connection with the wire 13.

The well 31 is electrically isolated by the barrier 44 from the screw shell 33. In it is seated, to one side of the wire passage 29, a terminal plate 45 carrying the binding screw 46 by which the bared end of wire 12 is electrically connected to the terminal plate. Where, as in the construction here illustrated, the socket is provided with a

switch, connection is established between this terminal plate and one of the switch contacts. The particular switch mechanism employed forms in general, no part of our invention and that here shown is of the common type described in the patent to Perkins No. 626,927, of June 13, 1899 which is desirable as affording a wide break on the opening of the switch. Current is led to the switch terminal 47 from the plate 45 through the bolt 48 which not only secures said plate in position but also secures upon the inner face of button *b*, the strap 49. One end of the switch terminal 47, which as a whole is guided in the recess 50 on meeting face of button *a*, overlies a tapped portion of the plate 49 and is clamped against the same by a screw 51 which passes through the button *a*, and a registering hole 52 in the terminal 47 and takes into the tapped plate 49. The switch block 53 makes and breaks contact with the terminal 47 in well understood manner on the rotation of the switch spindle 54. When in position to make contact the current is led through the switch block, frame 55 and screw 56 to the center contact 57 of the socket, thus completing the circuit through the lamp inserted therein.

Where the casing is one piece as here shown, it is obviously impossible to adjust the same upon the lamp body if the latter carries the usual switch key, since this would necessitate the slotting of the casing to an extent which would render it unmarketable. This difficulty has been overcome by making the key 58 detachable from the socket body and providing means for securing the same to the switch spindle after the socket body has been adjusted within its casing. To this end the switch spindle is provided at its outer end with a thimble 59 lying in the passage formed by the coöperating recesses 60 and 61 on the meeting faces of the buttons *a* and *b*. The outer end of the thimble is transversely slotted at 62, this slot terminating in an enlarged recess 63 in the body of the thimble. Coöperating with this thimble, the thumb piece or key 58 has a shank 64 with diametrically opposite wings 65 adapted to pass through the slot 62 in the thimble and enter the enlargement 63 thereof. The wings are of slightly greater thickness than the width of the slot 62 so that slight pressure is necessary to force the thimble open and permit the wings to pass through the slot. In adjusted position, the wings bear against the sides of the enlargement 63 and rotate the spindle in either direction to operate the switch, while they are normally held against escape by reason of the fact that it is necessary to exert some force to withdraw them through the slot 62. Obviously with this construction it is only necessary to provide a hole 66 in the casing which shall register with the

passage afforded by the recesses 60 and 61 in the socket body when the latter is in adjusted position. The thumb piece 58 may then be inserted through the hole 66 until the wings 65 on its shank pass through the slot 62 into the enlargement 63, whereupon the switch may be operated by turning the key in either direction.

The two buttons *a* and *b* of the insulating body are marketed in permanently assembled condition, with the head of the screw 51 "waxed-in" as also the head of the bolt 67 which passes up through both buttons and takes into the nut 68 waxed in its seat in the button *a*. The two buttons are thus held together, on one side by the bolt 48, strap 49 and screw 51 and on the other side by the straight through bolt 67 and its nut 68.

The manner of installing the device is readily understood. The wires having been pulled through the conduit and exposed, the shell 10 is secured to the threaded end of the conduit by screwing the nipple 11 thereon and fastening it by means of the set screw 69 in such position that the thumb piece 58 is readily accessible. The wires 12 and 13 are then passed through their respective passages 28 and 29 in the insulating body 16 which is shoved up and adjusted with the bracket feet 22 resting in the seats 23. The two securing screws 24 are then screwed into the bracket feet thus holding the socket body rigid with the shell. The ends of the wires are bared and clamped down beneath the binding screws 42, 46 and any extra length of wire cut off. The shank of the key 58 is then pushed through the hole 66 in the shell and into engagement with the split thimble 59 on the spindle, which is held in register with the hole in the shell by the predetermined position of the bracket 19 with relation thereto. The installation is thus complete.

The construction shown is an illustrative embodiment of our invention, but various changes may be made therein without departing from what we claim as our invention.

We claim as our invention:—

1. An electric lamp socket, comprising a one-piece metallic casing, an insulating body within the same and recessed at one end, lamp contacts located in said recess and carried by said body, said contacts comprising a center contact and a screw shell contact, in combination with wire terminals mounted on said body outside the area of the screw shell at the lamp-receiving end of the socket and screw means piercing the socket body outside the screw shell area and accessible from the lamp-receiving end of the socket for holding said body within the casing.

2. An electric lamp socket comprising a metallic casing, an insulating body within

- the same and recessed at one end to form a well, screw shell and center contacts mounted within said well and surrounded thereby, together with a pair of wire terminals 5 mounted on said body at the lamp-receiving end thereof and outside the area of the screw shell contact and electrical connections therefrom respectively to the lamp contacts.
3. An electric lamp socket, comprising a 10 metallic casing, an insulating body within the same and recessed at one end, a screw shell lamp contact seated in said recess, a center contact within said shell contact, in combination with wire terminals mounted at 15 the lamp-receiving end of the insulating body on opposite sides of said screw shell contact and electrical connections therefrom to the respective lamp contacts.
4. An electric lamp socket, comprising a 20 metallic casing, an insulating body within the same and recessed at one end, lamp contacts mounted within said recess and comprising a center contact and a screw shell contact, in combination with wire terminals 25 mounted on said body outside the area of said recess and at the lamp-receiving end of the socket.
5. An electric lamp socket, comprising a 30 metallic casing, an insulating body within the same recessed at one end to afford a well to receive a screw shell lamp contact, a bay opening from said well, a wire terminal lying in said bay and electrically connected to said screw shell, together with a recess 35 let into the lamp-receiving end of said body on the opposite side of the screw shell from said bay, a wire terminal seated in said recess and electrically insulated from said shell, a center lamp contact and electrical 40 connections between said wire terminal and center lamp contact.
6. An electric lamp socket comprising a 45 metallic casing, an insulating body within the same, lamp terminals carried thereby, wire terminals mounted at the lamp-receiving end of the body, wire passages through the body opening to the lamp-receiving end of the latter adjacent the wire terminals, and a switch arranged between at least one of said wire terminals and its lamp contact. 50
7. In an electric lamp socket, a casing, a socket body within the casing, a switch spindle carried by said body, the casing being apertured in line with said spindle, an operating thumb-piece sleeved on said spindle and a spring catch device for holding said thumb piece and spindle in assembled position. 55
8. In an electric lamp socket, a casing, a socket body within the casing, a switch spindle carried by said body, the casing being apertured in line with said spindle, and an operating thumb-piece detachably connected with said spindle, said connection being established through a wing piece 60 carried by one of said members, and a thimble carried by the other member and having an operating seat for said wing-piece and having slots leading to said seat through which said wing-piece may be 65 forcibly introduced to and spring-locked in said seat, substantially as described. 70
9. An electric lamp socket, comprising a one-piece casing having an aperture for the passage of a switch operating member therethrough, an insulating socket body carrying a switch and having a passage opening therethrough, a switch-operating member, a bracket rigid with said casing and means engaging said bracket for mounting said 75 body within the casing with said passage in register with the aperture in the casing.
- In testimony whereof we have signed our names to this specification, in the presence of two subscribing witnesses.
